CLAIM

The ornamental design for a barbecue grill shaped like a basketball, as shown and described.

DESCRIPTION

FIG. 1 is a top, front perspective view of a barbecue grill shaped like a basketball showing my new design;
 FIG. 2 is a rear elevational view thereof;
 FIG. 3 is a front elevational view thereof;
 FIG. 4 is a right side elevational view thereof;
 FIG. 5 is a left side elevational view thereof;
 FIG. 6 is a top plan view thereof; and,
 FIG. 7 is a bottom plan view thereof.

The broken lines showing the barbecue cart including the console panel, the side tables, the gas tank, and the logos are for illustrative purposes only and form no part of the claimed design.

1 Claim, 6 Drawing Sheets
